UNITED STATES PATENT OFFICE

108,261

DESIGN FOR A HANDBAG

Henri Felmann, Chicago, Ill.

Application December 20, 1937, Serial No. 73,726

Term of patent 3½ years

To all whom it may concern:

Be it known that I, Henri Felmann, a citizen of the United States of America, residing in Chicago, in the county of Cook, State of Illinois, have invented a new, original, and ornamental Design for a Handbag, of which the following is a specification, reference being had to the accompanying drawing, forming part thereof, wherein,

The rear portion of the handbag is identical in appearance to the front.

The circular elements shown on portions of the handbag represent pebble cloth, and are continued throughout the entire surface of the handbag.

I claim:

The ornamental design for a handbag, substantially as shown and described.

HENRI FELMANN.
